(57) **CLAIM**

What is claimed is the weldment fixture, as shown and described.

DESCRIPTION

FIG. 1 shows a side view of an embodiment of the weldment fixture according to the disclosure.

FIG. 2 shows a front view of the embodiment of the weldment fixture according to the disclosure.

FIG. 3 shows a top view of the embodiment of the weldment fixture according to the disclosure.

FIG. 4 shows a bottom view of the embodiment of the weldment fixture according to the disclosure; and,

FIG. 5 shows a perspective view of the embodiment of the weldment fixture according to the disclosure.
